UNITED STATES PATENT OFFICE.

HENRY H. SANFORD, OF DETROIT, MICHIGAN.

STOVE.

SPECIFICATION forming part of Letters Patent No. 661,707, dated November 13, 1900.

Application filed April 16, 1900. Serial No. 13,129. (No model.)

To all whom it may concern:

Be it known that I, HENRY H. SANFORD, a citizen of the United States, residing at Detroit, in the county of Wayne and State of Michigan, have invented certain new and useful Improvements in Stoves, of which the following is a specification, reference being had therein to the accompanying drawings.

The invention has reference generally to stoves or furnaces; and it consists in the peculiar construction of a stove whereby a minimum amount of smoke and soot will be formed by the burning fuel.

In the drawings illustrating my invention, Figure 1 is a vertical longitudinal section through the stove. Fig. 2 is a section taken on line xx , Fig. 1. Fig. 3 is a section on line yy of Fig. 2, showing the manner of attachment between the fire-pot and base-section and the means for supporting the grate. Fig. 4 is a perspective view of the grate, showing the parts thereof detached; and Fig. 5 is a section taken on line zz , Fig. 1.

In the drawings thus briefly described the reference-letter A designates the base-section of the stove, which may be of any desired construction and which is provided with inwardly-extending lugs a , preferably four in number, as plainly shown in Fig. 3. Mounted upon this section is the fire-pot B, provided with lugs b , corresponding in location and number and secured in any suitable manner to the lugs upon the base-section. In construction the fire-pot comprises an annular casting C, provided with a series of vertical slots or passages D formed in its inner face, the series extending circumferentially and entirely about the body, as shown. Each slot extends, preferably, from edge to edge of the fire-pot and tapers from the lower edge, where it is at its maximum width, to the top. Thus means are provided whereby the clogging or choking of ashes within the slots will be prevented.

45 C^2 is the stove-grate, which I preferably arrange upon the lugs b of the fire-pot.

It will be obvious from the construction of the mechanism as thus set forth that air admitted within the interior of the base-section 50 through suitable draft-openings in the door

F will be free to pass upwardly through the vertical passages or slots in the fire-pot, also that by coming in contact with the fuel it will cause the portion of the latter immediately adjacent to the wall of the fire-pot to 55 burn intensely and allow the central portion of the fuel to coke. The greater portion of the air continues in an upward direction through the slots and passes over the top of the fuel. At this point it mixes with the 60 gases driven off from the body of the fuel, and the mixture burns, thus preventing the formation of soot and smoke.

In order that the air from the base-section will be caused to travel upwardly through the 65 vertical passages in the fire-pot, it is essential that the ash-discharge openings in the grate upon which the fuel rests should be completely closed while the fuel is burning. Otherwise the path of the air will be through the 70 body of the fuel in the usual manner, producing the soot and smoke that it is desired to eliminate. To accomplish the desired result and also to provide means whereby the discharge of the ashes will not be interfered 75 with, I employ a type of grate the discharge-passages of which can be opened and closed at will.

In construction the grate comprises a lower section G, having a multiple of radial ash-discharge passages f and a central passage g formed therein, a similar rotatable section H, mounted thereon, having similar openings formed therein, and means for moving the rotatable section to bring the radial ash-discharge passages into and out of alignment for the purposes set forth. The lower section described rests, as before stated, upon the lugs b and is provided in turn with depending lugs b' at its periphery, so arranged upon 80 the section that they will abut against the lugs upon the fire-pot and prevent movement of the stationary section in either direction. The lower section is also provided on its lower face with guides i upon opposite sides of the 85 central opening, and arranged beneath said opening and having a sliding engagement with the guides is an imperforate plate H' , adapted to close the central opening of the grate. The plate is provided with extensions 90

j, permitting the plate to be reciprocated, and has extending from the front edge thereof a draw-bar *I*, which extends through a depending aperture lug or ear *J* upon the upper rotatable grate-section *H*.

In order that the shaking of the grate may be more easily effected, I have formed in the lower grate-section a series of circumferential ball-races *k* and arrange within said recesses 10 suitable balls *l*, thus forming a ball-bearing between the sections.

When the fire is under headway, the supply of air from the ash-pit section which passes over the top of the fuel is sufficient to prevent 15 the fire smoking. When new fuel is added to the fire, however, the air-supply is not sufficient to prevent the formation of soot and smoke, and I have therefore provided means whereby an additional supply of air may enter 20 over the top of the fuel from the side of the stove. The means I employ consists of a hollow ring *D'*, which I arrange upon the upper edge of the fire-pot casting and secure the parts together in any suitable manner. This 25 ring is provided with a series of apertures *D*², the apertures being formed in the lower wall of the ring and arranged one over each vertical slot in the casting, as shown. The ring is further provided with one or more draft- 30 openings, such as *D*³, in the outer side of the ring, controlled by a suitable slide-damper *D*⁴, adapted to be operated by a lug or handle *D*⁵. When fuel is added to the fire, the draft- 35 openings in the ring, which are normally closed, are opened, and an additional air-supply is provided for the gases, thereby eliminating the formation of the smoke and soot. The stove-grate is normally closed for the reasons before set forth, except at such times

when it is desired to remove the ashes, when 40 the grate is operated in the manner described.

What I claim as my invention is—

1. In a stove, the combination with the ash-pit section provided with a draft-passage leading into its interior, of the fire-pot above the 45 ash-pit section having a series of substantially vertical and circumferentially arranged air-passages formed in its inner surface, a grate at the bottom of the fire-pot, means for opening and closing the ash-discharge passages in the grate, whereby the entire draft through the ash-pit section may be caused to ascend through the series of passages in the fire-pot, and a hollow ring at the top of said fire-pot provided with an opening 55 or openings leading to the air-passages in the fire-pot and having one or more draft-openings formed therein.

2. In a stove, the combination with the ash-pit section, provided with one or more draft-passages leading into its interior, of a fire-pot above the ash-pit section having a series of substantially vertical and circumferentially-arranged air-passages formed in its inner surface, said passages communicating at their 65 lower ends with the ash-pit section, a grate at the bottom of the fire-pot, and a single closure device for the grate-openings, whereby the air in the ash-pit section may be caused to ascend either through the body of the fuel 70 or entirely along the sides of the latter, for the purpose set forth.

In testimony whereof I affix my signature in presence of two witnesses.

HENRY H. SANFORD.
